(57) **CLAIM**

The ornamental design for a coat hook, as shown and described.

DESCRIPTION

FIG. 1 is a perspective view of a coat hook showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view showing the coat hook installed to a coat rack with other coat hooks.

The broken lines in FIGS. 1-8 are for the purpose of illustrating portions of the coat hook that form no part of the claimed design. The dot-dash broken lines in FIGS. 1-3, 5-6 and 8 represent unclaimed boundary lines and form no part of the claimed design. The broken lines of the coat rack and the other coat hooks in FIG. 8 illustrate unclaimed environment and forms no part of the claimed design.
